UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

COAL CUTTING MACHINE

Application filed November 1, 1928, Serial No. 316,585. Renewed October 7, 1931.

The present invention relates to certain new and useful improvements in coal cutting machines, and particularly to machines of the class comprising a frame adapted to rest 5 upon and slide in any direction over the mine floor, a kerf cutter projecting horizontally therefrom, winding devices mounted upon the main frame and flexible draft devices attached to and windable upon said winding 10 devices adapted to cooperate with anchoring devices external of the machine to move and guide it relative to the material to be mined.

It is the especial object of this invention to provide, in a machine of the class described, an improved arrangement of parts whereby the external dimension of the machine may be reduced without impairment of the efficiency, strength or durability of the machine.

20 The means whereby I attain these and other objects are fully set forth in the following specification and illustrated in the accompanying drawings of which

Fig. 1 is a plan view of the preferred embodiment of my invention.

Fig. 2 is a side elevation of the machine illustrated in Fig. 1.

Fig. 3 is a fragmentary plan view of the rearward part of the machine illustrated in Figs. 1 and 2, certain parts being broken away to reveal other parts.

Fig. 4 is a sectional view taken along the line IV—IV of Fig. 3.

Fig. 5 is a sectional view taken along the line V—V of Fig. 3.

Fig. 6 is a rear elevation of the machine illustrated in Figs. 1 and 2, the cover plate being removed to reveal the feed controlling mechanism.

40 Fig. 7 is a view taken along the line VII—VII of Fig. 3.

Fig. 8 is a sectional view taken along the line VIII—VIII of Fig. 3.

Figs. 9, 10 and 11 are diagrams illustrating 45 some of the methods of operating the machine.

Like numerals refer to similar parts in the several figures.

As shown in the drawings the preferred 50 embodiment of my invention comprises a

main frame adapted to rest upon and slide in any direction over the floor of the mine, upon which the operative parts of the machine are supported. As here shown this main frame comprises three sections 1, 2 and 3, securely joined together by suitable bolts. The central section 2 consists of a single steel casting which constitutes the magnetic frame of an electric motor having a longitudinally extending armature 4 whereby the machine is actuated. The casting 2 also contains chambers wherein are mounted devices for the control of the actuation of the motor. Electric current for the actuation of this motor may be derived from any convenient source in any convenient manner but as such devices are well understood in the mining machine art, and as they form no part in the present invention, their illustration and description is not thought to be required at this time. 70

Rigidly secured to the forward frame section 1 and projecting horizontally therefrom is a cutter frame 5 having guideways formed in its lateral edges wherein travels the endless cutter chain 6 to which are attached the cutter bits 7 adapted to engage the coal to cut it. The chain 6 passes around and is actuated by a sprocket wheel 8 fixed to a vertical shaft 9 mounted in suitable bearings of the frame section 1, and is operatively connected with the armature shaft 4 of the motor by the bevel gears 10 and 11.

The rearward frame section 3 is built up of three castings 12, 13 and 14, securely joined together and to the motor frame 2 by suitable attachment bolts 15, and in the frame thus formed is mounted the feeding and guiding mechanism. The feeding and guiding mechanism comprises two winding drums 16 and 17 upon which are windable the feed ropes 18 and 19 adapted to cooperate with suitable abutments external of the machine. The drums 16 and 17 are mounted to revolve about vertical axes symmetrically positioned one at either side of the longitudinal center line 95 of the machine. Since the winding drums 16 and 17 and their actuating mechanisms are alike, a description of one will apply to both.

The drum 17 is mounted to revolve freely upon a hub 20 which, in turn, is eccentrically 100

rotatable about a stationary shaft 21 fixed to the frame of the machine. The hub 20 is provided with an arm 22 projecting horizontally to a position convenient to the hand of the operator. Formed on the inner face of the drum 17 are internal gear teeth adapted to engage the teeth of a pinion 23 formed integral with a vertical shaft 24 which is journaled in a bearing 25 formed in the casting 13 of the machine frame. The shaft 24 is operatively connected with the armature shaft 4 of the motor through a train of gearing comprising a planetary gear system which incorporates mechanism whereby the actuation of the drum 17 may be controlled. Keyed to the upper end of the shaft 24 is a wheel 26 the hub 27 of which forms a journal for the shaft 24 in the bearing 28 of the top casting 14 of the machine frame. The wheel 26 is provided with a downwardly projecting annular flange 29 having on its inner face gear teeth which engage the teeth of a plurality of pinions 30. The pinions 30 are freely rotatable upon stud shafts 31 fixed to the spider 32. The spider 32 has inwardly projecting bearing elements 33 engaging a bearing surface formed on the hub 27 of the wheel 26 to maintain said spider in concentric relation with the shaft 24. Other pinions 34 are formed integral with the pinions 30, and these pinions 34 engage a spur gear 35 fixed to the hub of the worm wheel 36 which is freely rotatable about the shaft 24. The worm wheel 36 engages a worm 37 formed integral with the worm shaft 38, and this worm shaft is supported in journal bearings 39 and 40 of the frame casting 13, which are positioned in the central longitudinal vertical plane of the machine coaxial with the armature shaft 4 to which the shaft 38 is connected by a shaft coupling 41. An annular flange 42 formed on the spider 32 is embraced by a brake band 43 engagement of which resists rotation of the spider 32. A second ring gear 44 supported by, but freely movable relative to the spider 32 engages the pinions 34, and this second ring gear 44 is embraced by a second brake band 45 whereby its rotation may be resisted.

The brake bands 43 and 45 are preferably formed of spring steel, or other suitable material having a relatively high coefficient of elasticity, and they are preferably lined with fibrous material, as shown at 46 in Fig. 4, to provide a suitable coefficient of friction. The said brake bands are formed with a curvature of somewhat greater diameter than the cylindrical surfaces which they embrace, and tend to spring away from said surfaces. A lug 47 fixed to one end of the brake band 45 engages the abutment 48 formed on the machine frame, and a similar lug 49 fixed to the other end of the same brake band engages a finger 50 which projects upwardly from a feed nut 51. Similar lugs 52 and 53 attached to the brake band 43 engage the abutment 54

of the machine frame, and the downwardly projecting finger 55 of the feed nut 51 respectively. The arrangement of these parts is such that movement of the nut 51 toward the right tightens the upper brake band 45 and releases the lower brake band 43 while movement of the said nut 51 toward the left tightens the lower brake band 43 and loosens the upper brake band 45. The brake band 45 is supported by the lugs 47 and 49 resting upon the upper surface of the feed nut 51 and a lug 57 attached to the middle of the brake band 45 engages a flange 58 of the machine frame. The brake band 43 is similarly supported, the lugs 52 and 53 resting upon a surface 59 of the machine frame.

The planetary system associated with the drum 16 is similar to that above described, and because the worm wheel 60 engages the worm 37 opposite to the worm wheel 30 the drum 16 will be driven in clockwise direction when the drum 17 is driven anti-clockwise. The brake bands 61 and 62 are similar to those above described having similar lugs 63 and 64 engaging abutments 65 and 66 of the frame, and lugs 67 and 68 engaging the fingers 69 and 70 of the feed nut 71.

The feed nut 71 is slidably supported in a guideway 72 formed in the machine frame, and is screw threaded to a shaft 73 which extends transversely of the machine. A flange 74 formed integral with the shaft 73, and a collar 75 screw threaded thereto engage opposite sides of a thrust collar 76 seated in a suitable recess of the machine frame which acts to prevent longitudinal movement of the shaft 73 in either direction. Fixed to the other end of the shaft 73 is a spur gear 77 which engages a similar gear 78 formed on a cylindrical sleeve 79 which projects through the machine frame and is journaled in a bearing 80 thereof. On the outer end of the sleeve 79 is formed a hand wheel 81 positioned convenient to the hand of the operator, by manipulation of which the shaft 73 may be rotated in either direction to cause longitudinal movement of the nut 71 in the guideway 72. The feed nut 51 is slidable in a guideway 82 formed in the machine frame, and is screw threaded to a sleeve 83 which is mounted concentrically of the shaft 73 and adapted to rotate relative thereto. A flange 84 formed integral with the sleeve 83, and a collar 85 screw threaded thereto, engage opposite sides of a thrust collar 86 which is seated in a suitable recess of the machine frame and acts to prevent longitudinal movement of said sleeve in either direction. A spur gear 87 formed integral with the thrust collar 85 engages a similar gear 88 fixed to the shaft 89. The shaft 89 is rotatably mounted in the sleeve 79 and to its projecting end is attached a second hand wheel 90 by the manipulation of which the sleeve 83 may be rotated to move the feed nut 51 longitudinally in its guide-

ways. The guideways 72 and 82, and the recesses for the thrust collars 76 and 86 are open rearwardly of the machine to facilitate the insertion or removal of the shaft 73 and its associated parts, and these parts are retained in operative position by the cover plates 91 attached to the frame castings 13 and 14 by suitable bolts.

When, by manipulation of the hand wheel 90, the feed nut 51 is moved to the left the brake band 43 will be tightened to prevent rotation of the spider 32 thereby causing the vertical shaft 24 to be driven to wind the feed rope 19 at a relatively fast speed suitable for handling the machine over the mine floor. When the feed nut 51 is similarly moved to the right, the brake band 45 will be tightened to prevent rotation of the ring gear 44, and thereby cause the vertical shaft 24 to be driven to wind the feed rope 19 at a relatively low speed suitable for feeding the cutting mechanism into the coal. When the feed nut 51 is in a central, or neutral, position, both of the brake bands 43 and 45 will be released from engagement with their respective driving elements, and the shaft 24 will remain idle. It is apparent that if the brake bands are partially tightened, permitting a greater or less degree of slippage between the brake bands and their respective driving elements, the speed of the shaft 24 will be proportionately reduced, and that these brake bands may act, under such circumstances, to retard rotation of the shaft 24 in a reverse direction.

By manipulation of the hand wheel 81 the shaft 92 may be driven in precisely the same manner as above described to cause the drum 16 to wind the feed rope 18 or to permit its unwinding under frictional control.

In the operation of this machine either of the ropes 18 or 19 may be used at relatively high speed to move the machine into position. When the machine has been suitably placed adjacent the coal face, as illustrated in Fig. 9, the levers 22 may be moved to disengage the drums 16 and 17 from their respective driving pinions, permitting the free rotation of the drums. The feed ropes 18 and 19 may then be drawn out and attached to the anchors 93 and 94 suitably positioned adjacent the coal face. When now the cutter chain 6 is actuated and the levers 22 restored to cause engagement of the drums 16 and 17, the hand wheels 81 and 90 may be manipulated to cause rotation of the drums 16 and 17 to wind both feed ropes 18 and 19 at relatively low speed to feed the cutter arm 5 longitudinally into the coal.

When the cutter arm 5 has been completely sumped, the lever 22 may be again moved to release the drum 17, the feed ropes 19 drawn therefrom, passed around the guide sheave 95 at the forward end of the machine frame, and attached to the anchor jack 96 at the

left hand rib adjacent the coal face, as illustrated in Fig. 10. At the same time the tail rope 18 will be moved to the anchor jack 97 positioned adjacent the right hand rib at a suitable distance from the coal face. The hand wheel 90 will now be manipulated to cause rotation of the drum 17 in a rope winding direction at feeding speed, and the hand wheel 81 manipulated to permit unwinding of the feed rope 18 under frictional resistance, to feed the cutter arm 5 laterally toward the left hand rib, and to maintain its angular relation with the coal face.

When it is desired to feed the machine from left to right, after reversing the cutter bits 7 in the sockets of the cutter chain 6, the direction of rotation of the armature 4 may be reversed, thereby reversing the direction of travel of the cutter chain 6, and the direction of rotation of the drums 16 and 17. The feed ropes 18 and 19 will then be drawn out completely from their respective drums, re-wound in the opposite direction, and attached to the jacks 98 and 99, as illustrated in Fig. 11, after which the operation will proceed as above described.

By the arrangement of parts above described, I have produced a coal cutting machine of small vertical dimensions, extreme durability, simplicity of design, and efficiency of operation. It is to be understood, however, that I do not limit myself to the precise construction here shown since the machine may be subject to wide variation as to details without departure from the spirit of my invention.

What I claim is:

1. In a machine of the class described, the combination with a frame adapted to rest upon and slide in any direction over the floor of a mine, of mining mechanism mounted thereon, feeding and guiding mechanism comprising two flexible draft elements adapted to cooperate with anchoring devices external of the machine, two winding drums mounted for rotation about vertical axes and adapted to wind said draft elements, and optionally controlled power actuated means to cause rotation of either or both of said drums in a winding direction either simultaneously or separately at either of two speeds or to cause the simultaneous rotation of the drums each at a different speed as and for the purpose set forth.

2. In a machine of the class described, the combination with a frame adapted to rest upon and slide in any direction over the floor of a mine, of mining mechanism mounted thereon, feeding and guiding mechanism comprising two flexible draft elements adapted to cooperate with anchoring devices external of the machine, two winding drums mounted for rotation about spaced apart vertical axes and adapted to wind said draft elements, and optionally controlled power ac-

tuated means to cause rotation of either or both of said drums in a winding direction either simultaneously or separately at either of two speeds or to cause the simultaneous 5 rotation of the drums each at a different speed as and for the purpose set forth.

3. In a machine of the class described, the combination with a frame adapted to rest upon and slide in any direction over the floor 10 of a mine, of mining mechanism mounted thereon, feeding and guiding mechanism comprising two flexible draft elements adapted to cooperate with anchoring devices external of the machine, and two similar winding drums mounted for rotation about vertical axes and adapted to wind said draft elements, and optionally controlled power actuated means to cause rotation of either or both of said drums in a winding direction 15 either simultaneously or separately at either of two speeds or to cause the simultaneous rotation of the drums each at a different speed as and for the purpose set forth.

4. In a machine of the class described, the combination with a frame adapted to rest upon and slide in any direction over the floor 20 of a mine, of mining mechanism mounted thereon, feeding and guiding mechanism comprising two flexible draft elements adapted to cooperate with anchoring devices external of the machine, two winding drums mounted upon the frame for rotation about vertical axes and adapted to wind said draft elements and optionally controlled power actuated means to 25 cause rotation of either or both of said drums in a winding direction either simultaneously or separately or to cause the simultaneous rotation of the drums each at a different speed or to permit the free rotation of either or both of said drums as and for the purpose set forth.

5. In a machine of the class described, the combination with a frame adapted to rest upon and slide in any direction over the floor 30 of a mine, of mining mechanism mounted thereon, a motor for actuating said mining mechanism, feeding and guiding mechanism comprising two flexible draft elements adapted to cooperate with anchoring devices external of the machine, two winding drums mounted upon said frame for rotation about vertical axes and adapted to wind said draft elements, an independent planetary gearing 35 associated with each of said drums and connected with said motor, and means to optionally control said planetary gearings to cause rotation of either or both of said drums in a winding direction either simultaneously or separately at either of two speeds or to permit their controlled rotation in the unwinding direction as and for the purpose set forth.

6. In a machine of the class described, the combination with a frame adapted to rest 40 upon and slide in any direction over the floor 45 of a mine, of mining mechanism mounted thereon, a motor for actuating the mining mechanism, feeding and guiding mechanism comprising two flexible draft elements adapted to cooperate with anchoring devices external of the machine, two winding drums mounted upon the frame for rotation about vertical axes symmetrically disposed in a transverse vertical plane one at either side of the longitudinal center line of the machine and adapted to wind said draft elements, an independent planetary gearing 50 associated with each of said drums and connected with said motor, and means to optionally control said planetary gearings to cause rotation of either or both of said drums in a winding direction either simultaneously or separately at either of two speeds as and for the purpose set forth.

of a mine, of mining mechanism mounted thereon, a motor for actuating said mining mechanism, feeding and guiding mechanism comprising two flexible draft elements adapted to cooperate with anchoring devices external of the machine, two winding drums mounted upon said frame for rotation about vertical axes and adapted to wind said draft elements, an independent planetary gearing 70 associated with each of said drums and connected with said motor, means to optionally control said planetary gearings to cause rotation of either or both of said drums in a winding direction either simultaneously or separately at either of two speeds or to permit their controlled rotation in an unwinding direction, and means to permit free rotation of said drums as and for the purpose set forth.

7. In a machine of the class described, the combination with a frame adapted to rest upon and slide in any direction over the floor of a mine, of mining mechanism mounted thereon, a motor for actuating the mining mechanism, feeding and guiding mechanism comprising two flexible draft elements adapted to cooperate with anchoring devices external of the machine, two winding drums mounted upon the frame for rotation about vertical axes symmetrically disposed in a transverse vertical plane one at either side of the longitudinal center line of the machine and adapted to wind said draft elements, an independent planetary gearing 80 associated with each of said drums and connected with said motor, and means to optionally control said planetary gearings to cause rotation of either or both of said drums in a winding direction either simultaneously or separately at either of two speeds as and for the purpose set forth.

8. In a machine of the class described, the combination with a frame adapted to rest upon and slide in any direction over the floor of a mine, of mining mechanism mounted thereon, a motor for actuating the mining mechanism, feeding and guiding mechanism comprising two flexible draft elements adapted to cooperate with anchoring devices external of the machine, two winding drums mounted upon the frame for rotation about vertical axes symmetrically disposed in a transverse vertical plane one at either side of the longitudinal center line of the machine and adapted to wind said draft element, an independent planetary gearing 90 associated with each of said drums and connected with said motor, means to optionally control said planetary gearings to cause rotation of either or both of said drums in a winding direction either simultaneously or separately at either of two speeds as and for the purpose set forth.

- trolling means as and for the purpose set forth.
9. In a machine of the class described, the combination with a frame adapted to rest upon and slide in any direction over the floor of a mine, of mining mechanism mounted thereon, a motor for actuating said mining mechanism, feeding and guiding mechanism comprising two flexible draft elements adapted to cooperate with anchoring devices external of the machine, two winding drums mounted upon said frame for rotation about vertical axes and adapted to wind said draft elements, gearing associated with each of said drums and actuated by said motor, and means to optionally control said gearing to cause rotation of either or both of said drums in a winding direction either simultaneously or separately at either of two speeds or to cause the simultaneous rotation of the drums each at a different speed or to permit their controlled rotation in an unwinding direction as and for the purpose set forth.
10. In a machine of the class described, the combination with a frame adapted to rest upon and slide in any direction over the floor of a mine, of mining mechanism mounted thereon, a motor for actuating said mining mechanism, feeding and guiding mechanism comprising two flexible draft elements adapted to cooperate with anchoring devices external of the machine, two winding drums mounted upon said frame for rotation about vertical axes and adapted to wind said draft elements, gearing associated with each of said drums and actuated by said motor, means to optionally control said gearing to cause rotation of either or both of said drums in a winding direction either simultaneously or separately at either of two speeds or to cause the simultaneous rotation of the drums each at a different speed or to permit their controlled rotation in an unwinding direction as and for the purpose set forth.
11. In a machine of the class described, the combination with a frame adapted to rest upon and slide in any direction over the floor of a mine, of mining mechanism mounted thereon, a motor for actuating said mining mechanism, feeding and guiding mechanism comprising two flexible draft elements adapted to cooperate with anchoring devices external of the machine, two winding drums mounted upon said frame for rotation about vertical axes and adapted to wind said draft elements, gearing associated with each of said drums and actuated by said motor to cause rotation of said drums in opposite direction, and means to optionally control said gearing to cause rotation of either or both of said drums at either of two speeds or to cause the simultaneous rotation of the drums each at a different speed as and for the purpose set forth.
12. In a machine of the class described, the combination with a frame, of a horizontally disposed power actuated shaft rotatably mounted in said frame, a worm fixed to said shaft, two worm wheels mounted for rotation about vertical axes and engaging opposite sides of said worm, a winding drum rotatable about a vertical axis positioned beneath each of said worm wheels, a system of gearing above each of said worm wheels arranged to operatively connect the respective drums and worm wheels, and means to control each of said systems of gearing to cause rotation of its drum at either of two speeds as and for the purpose set forth.
13. In a machine of the class described, the combination with a frame, of a horizontally disposed power actuated shaft rotatably mounted in said frame, a worm fixed to said shaft, two worm wheels mounted for rotation about vertical axes and engaging opposite sides of said worm, a winding drum rotatable about a vertical axis positioned beneath each of said worm wheels, a system of gearing above each of said worm wheels arranged to operatively connect the respective drums and worm wheels, and means to control each of said systems of gearing to cause rotation of its drums at either of two speeds or to permit its controlled rotation in the opposite direction as and for the purpose set forth.
14. In a machine of the class described, a frame, a motor on said frame, a power transmitting shaft extending longitudinally of the frame, a pair of winding drums at the rear of said frame rotatable about vertical axes symmetrically disposed at either side of said shaft, a worm gear associated with each of the drums and disposed on an axis parallel to a line parallel to the axis of its associated drum, driving connections between said gears and drums, and a worm on said shaft engaging each of said gears.
15. In a machine of the class described, a frame including a base plate forming supporting means for the rear of the frame, a motor on said frame, a power transmission shaft extending longitudinally of the frame, a pair of winding drums rotatable immediately above said base plate about vertical axes symmetrically disposed at either side of said shaft, a worm gear associated with and above each of the drums and disposed on an axis parallel to a line parallel to the axis of its associated drum, driving connections between said gears and drums, and a worm on said shaft engaging each of said gears.
16. In a machine of the class described, a frame, a motor on said frame, a power transmission shaft extending longitudinally of the frame, a pair of winding drums at the rear of the frame rotatable about vertical axes symmetrically disposed at either side of said shaft, a worm gear associated with each of the drums and disposed on an axis parallel

to a line parallel to the axis of its associated drum, planetary change speed gearings coaxially disposed relative to the worm gears and connecting the respective gears and drums, and a worm on said shaft engaging said gears.

17. In a machine of the class described, the combination with a single worm, of two worm wheels in mesh with said worm and mounted 10 for rotation on spaced-apart vertical axes, two rope drums mounted for rotation on two spaced-apart vertical axes, variable speed power transmission mechanism between said worm wheels and said rope drums, and means 15 for controlling said power-transmission mechanism to secure variable speeds of rotation of either or both of said rope drums independently of each other.

18. In a machine of the class described, the combination with a supporting frame, of a motor thereon having a longitudinally extending armature shaft, a worm on said shaft, worm gears on opposite sides of said worm with their axes vertical at the rear end portion 25 of the frame, rope drums mounted at the rear end portion of the machine, and separate and independently controlled plural speed transmission mechanisms between said worm gears and said rope drums.

19. In a machine of the class described, the combination with a supporting frame, of two rope drums mounted thereon for rotation on vertical spaced-apart parallel axes, two variable speed power transmission mechanisms 30 one connected to one rope drum and the other to the other rope drum, and means for controlling said variable speed power transmission mechanisms independently of each other to secure rotation of either rope drum independently of the rotation of the other rope drum.

20. In a mining machine, the combination with a supporting frame adapted to rest on and slide over the mine floor, of kerf-cutting 45 mechanism on the forward end of said frame, feeding and guiding mechanism on the rear end of said frame comprising rope drums mounted for rotation on vertical axes, a motor on said frame, and a single longitudinal shaft 50 connecting said motor to said cutting mechanism and extending to a position between the axes of said rope drums for connection to the latter.

21. In a low vein mining machine, the combination with a supporting frame, of kerf-cutting mechanism connected to the forward end thereof, feeding and guiding mechanism comprising two rope drums mounted for rotation on vertical spaced-apart parallel axes 60 on the rear end of said frame, a motor mounted on said frame between the top and bottom surfaces thereof, a central longitudinal motor shaft connected at its forward end to said cutting mechanism and extending at its 65 rear end to a position between said vertical

axes of said rope drums, a worm on said longitudinal shaft, and two worm wheels meshing with said worm and connected to said feeding and guiding mechanism to drive the same.

22. In a low vein mining machine, the combination with a supporting frame, of kerf-cutting mechanism on the forward end of said frame, feeding and guiding mechanism on the rear end of said frame and comprising 70 two rope drums mounted to rotate on vertical spaced-apart parallel axes, a motor on said supporting frame, a driving connection between said motor and said kerf-cutting mechanism, a worm connected to said motor to be driven thereby, two worm wheels meshing with said worm, and separate variable speed power transmission mechanisms one between 75 one of said worm wheels and the feeding rope drum and the other between the other worm wheel and the guiding rope drum.

23. In a low vein mining machine, the combination with a supporting frame, of cutting mechanism on the front end thereof, feeding and guiding mechanism on the rear end of said frame and comprising rope drums mounted for rotation on vertical axes, a worm connected to said motor to be driven thereby, two worm wheels always in mesh with 80 said worm, and separate and independent variable speed power transmission units one connected between one of said worm wheels and the feeding rope drum and the other connected between the other worm wheel and the guiding rope drum.

24. In a low vein mining machine, the combination with a supporting frame adapted to rest on and slide over a mine floor, of an elongated chain kerf-cutter connected to the forward end of said frame, feeding and guiding mechanisms on the rear end of said frame and comprising two rope drums mounted for rotation on vertical axes, a motor on the frame between the upper and lower surfaces thereof, a driving connection between said 90 motor and said chain kerf-cutter, a driving worm connected to said motor and located at the rear end of said frame, two worm wheels meshing with said worm and mounted to rotate on vertical axes, and two separate and independent variable speed power transmission units one connected between one of said worm wheels and the feeding rope drum and the other connected between the other worm wheel and the guiding rope drum.

25. In a low vein mining machine, the combination with a supporting frame, of an elongated chain kerf-cutter on the forward end of said frame, feeding and guiding mechanism symmetrically arranged on the rear end of said frame and comprising two rope drums mounted for rotation on parallel spaced-apart vertical axes, a motor on said frame between the upper and lower surfaces thereof, a longitudinal central motor shaft con- 110 115 120 125 130

- nected at its forward end to said kerf-cutter and extending at its rear end to a position between said vertical axes, a worm on the rear end of said shaft, two worm wheels meshing with said worm and symmetrically arranged to rotate on vertical spaced-apart parallel axes, and two separate and independent variable speed power transmission units coaxial respectively with the vertical axes of said 5 worm wheels and one connected between one worm wheel and the feeding rope drum and the other connected between the other worm wheel and the guiding rope drum.
26. In a mining machine, the combination 10 with a frame adapted to rest on and slide over a mine floor, of cutting mechanism carried thereby, a motor connected to said cutting mechanism to drive the same, and apparatus for effecting sliding of said frame 15 over the mine floor comprising a feeding rope drum and a guiding rope drum, two plural speed transmission units one connected to the feeding rope drum and the other connected to the guiding rope drum, separate and 20 independent controlling mechanisms one associated with one of said units and the other associated with the other unit, and power transmission mechanism comprising a single pair of worm gear wheels connected between 25 said motor and said units.
27. In a mining machine, the combination 30 with a frame, of cutting mechanism carried thereby, a motor connected to said cutting mechanism to drive the same, and apparatus for feeding and guiding the machine comprising a feed rope drum and a guide rope drum, a plural speed transmission unit for the feed drum, a separate plural speed transmission unit for the guide rope drum, mechanism 35 for controlling the unit for the feed drum, separate mechanism for controlling the unit for the guide drum, and power transmission mechanism having only one pair of gear wheels one connected to one of said units 40 and the other connected to the other unit.
28. In a mining machine, the combination 45 with a frame, of cutting mechanism thereon, a motor connected to said cutting mechanism to drive the same, feeding mechanism comprising rope drums rotatable on vertical 50 axes, and motor operated means for driving said rope drums including a fast and slow speed gear train for each rope drum and capable of driving only the rope drum to which 55 it is connected, all of the gears of said gear trains rotating on vertical axes at either speed.
29. In a mining machine, the combination 60 with a frame, of cutting mechanism carried thereby, a motor connected to said cutting mechanism to drive the same, feeding mechanism comprising rope drums rotatable on vertical axes, plural speed transmission mechanisms one for each rope drum and each 65 capable of driving only the rope drum to 70 which it is connected, said transmission mechanisms each having a fast and slow speed gear train the initial and final gears of which are on fixed axes.
30. In a mining machine, the combination 75 with a frame, of cutting mechanism thereon, a motor for driving said cutting mechanism, feeding mechanism including rope drums rotatable on vertical axes and each having a draft rope connected thereto and wound thereon and extending therefrom, motor operated means for said rope drums including a fast and slow speed gear transmission mechanism for each rope drum, the gear transmission mechanism connected to each rope drum 80 not being capable of driving the other rope drum, the initial and final gears of each transmission mechanism rotating on fixed axes during drive at either speed.
- In testimony whereof I have hereunto set 85 my hand.
- NILS D. LEVIN.
